UNITED STATES PATENT OFFICE.

LUTHER C. DEAR, OF BUTTE, MONTANA

SLIDABLY-ADJUSTABLE BRACKET.

1,128,419.

Specification of Letters Patent. Patented Feb. 16, 1915.

Application filed January 9, 1914. Serial No. 811,230.

To all whom it may concern:

Be it known that I, LUTHER C. DEAR, a citizen of the United States, residing at Butte, in the county of Silverbow, State of Montana, have invented certain new and useful Improvements in Slidably-Adjustable Brackets; and I do hereby declare the following to be a full, clear, and exact description of the invention, such as will enable others skilled in the art to which it appertains to make and use the same.

This invention relates to new and useful improvements in brackets, and particularly that class which are slidably adjustable on a rod or similar supporting means.

The object of the present invention resides in the provision of a bracket which is slidably adjustable on a rod or similar supporting means and which is held in said adjusted position by the weight or the tension exerted by the article held by the said bracket.

A more specific object resides in the provision of brackets adapted for holding copper plates in an electrolytic leaching apparatus, whereby the relatively thin plates may be readily and quickly secured in place and held against buckling.

A further object resides in the provision of brackets of the above type of such design that they may be very cheaply manufactured.

With these and other objects in view, the invention resides in the novel combination and arrangement of parts to be hereinafter described and illustrated in the accompanying drawings and particularly pointed out in the claim hereto appended.

Reference is had to the accompanying drawings wherein similar characters of reference designate corresponding parts throughout the several views and in which:

Figure 1 is a side elevation of the adaptation of the invention for holding articles for display, Fig. 2 is a perspective view of the bracket shown in Fig. 1, Fig. 3 is a view showing the adaptation of the invention for supporting curtains or the like, Fig. 4 is a perspective view showing a modified and more ornamental form of bracket for holding curtains or the like, Fig. 5 is a side elevation showing the adaptation of the device for suspending copper plates, and Fig. 6 is a sectional view on the line 6—6 of Fig. 5.

Referring now more particularly to Figs. 1 and 2 of the drawings wherein the brackets are used preferably for displaying articles, 5 designates a vertical cylindrical main supporting rod. Each of the brackets comprises a shank portion 6 provided at one end with suitable means 7 for engaging an article to be displayed. The other end portion of the shank is bent in substantially U-shape at 8 and is then bent downwardly at 9 and terminates in a lateral portion 10 lying transversely of and engaging the rod. It is observed that this bracket is freely slidable on the rod and can be readily positioned thereon. When however, weight is placed on the free end of the shank the bracket swings with its U-shape portion 8 as a pivot and binds the transverse portion 10 against the rod to effectually prevent sliding movement.

Referring now to Fig. 3 of the drawings, wherein the device is used as a curtain support, the main supporting bar 11 is disposed horizontally. A pair of brackets are provided including the U-shaped portions 12 and the transverse portions 13 as above-described. The free ends of the shanks of these brackets are directed laterally at 14 to form hooks which engage in the ends of the curtain. The brackets are slid in opposite directions along the bar until the curtain is properly positioned, and the normal tension of the curtain holds the brackets against undesired displacement.

In the more ornamental structure shown in Fig. 4 of the drawings, brackets are provided as in Fig. 3 and include the U-shaped portions 15, the transverse portions 16 and the hook portions 17. In this form the transverse portions are extended and have threaded thereon ornamental caps 18. The free ends of the bills of the hooked portions 17 are laterally directed at 19 and have threaded thereon the ornamental caps 20. Curtains may be held in the usual manner by the hooks 17 or they may be secured to and held by the transverse portions 16. In the latter instance, the transverse portions by the tension exerted thereon swing the U-shaped portions 15 into binding engagement with the rod.

In Figs. 5 and 6, wherein is shown the adaptation of the invention for preventing copper plates as in an electrolytic leaching apparatus, the usual horizontal bar, design-

nated at 21 is provided. A pair of brackets are provided, and comprise the shanks 22, the U-shaped portions 23 and the transverse portions 24 which are in this instance flattened so that they engage the rod 21 in such manner as to facilitate the passage of electric current therethrough. The free ends of the shanks are provided with hooks 25 which engage in openings 26 formed in the upper corners of the plate 27. The plate may be thus suspended from the brackets, and to prevent buckling thereof the brackets are drawn away from each other on the bar and are held in this position by the engagement of their transverse portions 24 with the bar, due to the tension exerted by the resiliency of the shanks.

From the foregoing it is observed that a very simple form of bracket has been provided which may be adapted to a variety of uses. It will be noted that the bracket comprises only a single length of wire and may thus be very cheaply manufactured. It will be further understood that this device instead of being formed with wire, may be formed of relatively large metal rods or the like, so that it may be used for such pur-

poses as supporting scaffolds on buildings or the like.

What is claimed is:

In a device of the class described, the combination with a horizontal supporting rod of a pair of spaced brackets depending therefrom, each comprising a resilient shank having one end portion bent to embrace the upper side of the bar, then bent downwardly parallel with the shank, bent again at right angles to said downwardly bent portion and terminating in a portion extending transversely and engaging the lower side of the bar, and hooks on the other ends of said shanks adapted to support an article, the right angular bent portions of the brackets extending toward each other and the resilience of said shanks being oppositely and outwardly directed, whereby an article supported on said hooks will be subjected to endwise tension.

In testimony whereof, I affix my signature, in the presence of two witnesses.

LUTHER C. DEAR.
